The ornamental design for a pulp press or a portion thereof, as shown and described.

DESCRIPTION

FIG. 1 is a top-side perspective view of a pulp press.

FIG. 2 is a bottom-side perspective view of the pulp press of FIG. 1.

FIG. 3 is a side plan view of the pulp press of FIG. 1.

FIG. 4 is a top plan view of the pulp press of FIG. 1; and, FIG. 5 is a bottom plan view of the pulp press of FIG. 1. The broken line showing of elements on the pulp press illustrate portions of the article and form no part of the claimed design.

The different shading in the handle and/or the base of the pulp press indicate a contrast in texture and/or material.

Depicted right-left and left-right diagonal lines, as shown in FIGS. 52-54 and 56-58, represent a continuous or semi-continuous plane surface of the same or different materials and/or textures.

Color may or may not form part of the claimed design without departing from the design disclosed. The inventors anticipate that the invention can be any part, portion, element, or combination of elements of the depicted design.
